UNITED STATES PATENT OFFICE.

HERMAN KAPOTKIN, OF NEW YORK, N. Y.

DESIGN FOR A SOFT-COLLAR CLASP.

59,009.

Specification for Design.

Patented Sept. 13, 1921.

Application filed March 25, 1921. Serial No. 455,639. Term of patent 7 years.

To all whom it may concern:

Be it known that I, HERMAN KAPOTKIN, a citizen of the United States, residing in New York, in the county and State of New York, have invented a new, original, and ornamental Design for a Soft-Collar Clasp, of which the following is a specification, reference being had to the accompanying drawing, forming a part thereof, and in which—

Figure 1 is a perspective view of a clasp made in accordance with my new design looking from the outer or front side.

Fig. 2 is a similar perspective view of the same looking from the under side thereof.

I claim:—

The ornamental design for a soft collar clasp as shown.

HERMAN KAPOTKIN.
